UNITED STATES PATENT OFFICE.

JAMES E. GANNON AND MONTAGUE W. WARD, OF ERIE, PENNSYLVANIA; SAID WARD
ASSIGNOR TO JOHN MARK GANNON, OF ERIE, PENNSYLVANIA.

SYSTEM FOR HEATING WATER.

Application filed December 29, 1926. Serial No. 157,774.

This invention relates to heaters for hot water and consists of a boiler tank in which is placed an electric heating unit which is connected to a source of energy and which 5 may be switched on and off at will. Also a thermostatically controlled automatic switch to throw off the current when the water becomes sufficiently heated, and to throw the current on again when the water lowers in 10 temperature.

These and other features will appear hereafter, and will be fully pointed out and explained.

The features of our invention are illustrated in the accompanying drawings in which:

Figure 1 is a vertical central section of a water heater embodying our invention.

Figure 2 is a diagrammatic drawing of 20 the thermo-automatic switch of our invention.

In these drawings A indicates the shell of a water boiler, A' indicates the head thereof and A² indicates the bottom of the boiler. 25 Through the side wall A of the shell is placed a cylindrical member B having an opening B' through the under side of the wall thereof of adjacent to the wall A of the boiler.

The member B is inclined upward and 30 upon the end thereof we place a connection B², and in the connection B² we place an upright tube C which extends nearly to the head A' of the boiler. Within the upwardly inclined member B we place an electric heating unit D to which are secured wires E and E' which extend to a switch board F located 35 in the base of the boiler. This switch board is provided with a switch mechanism F' by means of which connection is made with the wires G and G' leading to a source of energy.

At a suitable distance downward from the head A' of the boiler we place a thermostat H which has an arm H' projecting through 45 the wall A of the boiler into the water contained therein, which when the water becomes heated sufficiently operates the mechanism within the thermostat H.

Within the thermostat H is a mercury tube J, see Fig. 2 which has been tilted by the thermostat arm H' so that the mercury therein, shown by broken line, runs toward one end of the tube J and emerges the ends of the wires J' and J², and thereby makes a connection between them.

Behind the switch board F in the base of

the boiler is a magnetically operated make and break switch K having magnetic coils K' and K². The wire J' shunts from the wire E, runs through the magnetic coil K' to the mercury tube J of the thermostat, thence through the mercury to the wire J² and thence to the line E', thus magnetizing the coil K' and holds the switch K in contact with the contact post k through which the circuit is maintained.

When the temperature of the water in the boiler is lowered sufficiently the mercury tube J tips the other way and the mercury therein slides to the opposite end of the tube, thus breaking the circuit between the terminals 70 of the wires J' and J², and emersing the ends of the terminals of the wires J² and J³, thus completing the circuit through the wires J² and J³ and magnet coil K². The shunt circuit branching off of the line E' and returning to the line E, thus magnetizing the coil K² and drawing the switch away from the contact post k, breaking the circuit through the heating unit D. The circuit remains broken until the temperature of the 80 water in the boiler causes the mercury tube J to reverse itself again, when the heating unit will be heated again.

In the boiler itself the tubes B and C separate the circulation of warm water from the 85 body of the cold water, the water entering the tube B through the opening B' adjacent to the lower end thereof, and leaving the upper end of the tube C, and mixing with the body of the water in the boiler A until the body 90 of water in the boiler becomes heated sufficiently down to the thermostat arm H'. It is estimated that there will be enough water heated in the upper end of the boiler to furnish a bath, and by the time more is needed 95 the heating unit will function sufficiently to supply it.

Having thus fully shown and described suitable mechanism and apparatus to automatically supply hot water, so that others can 100 utilize our invention, we do not desire to be limited to the exact arrangement shown and described as many modifications can be made therein without departing from the scope of our invention, therefore what we claim as 105 new and desire to secure by Letters Patent is:

In a system for heating water, a tank, an electric heating unit within said tank, a main electric circuit including a make and break 110

device, a shunt circuit including a magnetic coil connected with said main circuit, a make and break device in said shunt circuit by means of which said shunt circuit can be closed, a second shunt circuit including a magnetic coil connected with said main circuit, a make and break device in said second shunt circuit by means of which said second

shunt circuit can be closed, and a thermostatic device actuated by the temperature of the water in said tank to alternately energize said magnetic coils. ¹⁰

In testimony whereof we affix our signatures.

JAMES E. GANNON.
MONTAGUE W. WARD.
